UNITED STATES PATENT OFFICE.

WILLIAM SPARKS, OF JACKSON, MICHIGAN, ASSIGNOR TO THE SPARKS-WITHINGTON COMPANY, A CORPORATION OF OHIO.

OPERATING MECHANISM FOR SIGNALS AND THE LIKE.

1,239,055.

Specification of Letters Patent.

Patented Sept. 4, 1917.

Original application filed November 14, 1913, Serial No. 800,955. Divided and this application filed June 10, 1914. Serial No. 844,152.

To all whom it may concern:

Be it known that I, WILLIAM SPARKS, of Jackson, in the county of Jackson, in the State of Michigan, have invented new and useful Improvements in Operating Mechanism for Signals and the like, of which the following, taken in connection with the accompanying drawings, is a full, clear, and exact description.

10 This invention relates to certain improvements in signals and more particularly to mechanically operated signals of the diaphragm type, and although susceptible of many and varied uses is particularly for use 15 in connection with automobiles, motor-boats and other moving bodies, and is a division of my co-pending application Serial No. 800,955, filed November 14, 1913, which application contains the broad claims to the 20 signal, while the claims of this application relate broadly to means for changing reciprocal motion into rotary motion, particularly adapted for use in the signal disclosed herein but susceptible of use in any other construction or place where it is desired to convert reciprocal motion into rotary motion, and the claims herein are therefore not limited 25 to signals or any other particular use, construction or device.

30 The primary object of the invention is to provide a simple and comparatively inexpensive construction for changing reciprocal motion into rotary motion by means of which the speed of the rotary motion can be easily 35 determined and the extent of the same can be accurately governed. The particular construction by which this is accomplished is applicable to many and various uses, and as illustrative of one of such uses the same 40 is shown in connection with a diaphragm horn in which the actuator for the diaphragm is mounted upon the element to which rotary movement is adapted to be given.

45 Other objects and uses appear in the details of construction and arrangement illustrated in the accompanying drawings, in which—

50 Figure 1 is a central, longitudinal, cross section of a signal illustrating the use of this invention.

Fig. 2 is a top plan view partially in section, the amplifier being omitted.

Fig. 3 is a view of the ratchet case with its cover removed.

Fig. 4 is a view of the operating nut formed with a ratchet face.

Fig. 5 is a side elevation of one of the operating jaws engaging with the ratchet clutch.

60 The signal as shown comprising a diaphragm —1— having its marginal portion confined between the base of an amplifier —2— and a suitable case section —3— connected by screws —4— passed through the 65 amplifier section —2— and threaded into the case section —3—, although this construction may be reversed or any other suitable connecting means substituted.

65 The base of the amplifier is obliquely disposed with respect to the plane of the diaphragm and a portion of the case section —3— is similarly obliquely disposed and provided with a depressed central portion —5— to form a diaphragm case within 70 which the diaphragm may freely vibrate.

75 A cup shape casing —6— of slightly greater diameter than the depressed portion of the case section —3—, slidably engages the circumferential flange —7— formed by 80 depressing the portion —5— of the section —3— and is secured thereto by means of screws —8—, although any other suitable means may be substituted therefor. The casing —6— is provided with opposite bearings —9— and —10— preferably having 85 conical sockets as shown for the reception of a squared conical ended shaft —11—.

90 The bearing —9—, as shown, may be rigidly secured to the casing —6— in any suitable manner as by welding, or it may be a removable adjustable bearing similar to the bearing —10— which, in this instance, is formed by having the bearing —10— externally threaded for coaction with an internally threaded portion of the casing —6— and preferably having a similar threaded relation with a reinforcing plate —12— positioned within the casing, so that the bearing is adjustable through the casing and may be located in any of its adjusted 95 positions by means of the nut —13—.

The upper portion of the shaft —11— is twisted so as to form a spiral of suitable pitch so that a coacting nut —14—, if held from rotation and moved along said shaft, 5 will cause rotation of the same. For the purpose of holding said nut from rotation when moved in one direction and thereby causing rotation of the shaft —11— and for allowing a return of said nut to normal position on the shaft without rotation of said shaft by allowing the nut itself to rotate upon the return movement, a case —15— is provided adapted to be positioned on said shaft —11— and having a seat —16— formed 10 concentric with the shaft opening —17— for the reception of the nut —14— which has one of its faces provided with a plurality of ratchet teeth having abrupt radial faces on one side only, and adapted to engage 15 projections or stops —18— when the ratchet is turned in one direction and to freely ride over said stops when moving in the other direction.

The case —15— is sufficiently deep to permit nut —14— to lie in a position at which the teeth thereon will not engage the stops —18— upon the case. This is the condition when the nut lies in contact with the cover —19—. In other words, the chamber 30 within the case is of sufficient depth to allow nut —14— with the teeth thereon to move out of engagement with the stops upon the case so that the nut may freely rotate within and with respect to the case.

35 When the case is moved downwardly by the operating handle, nut —14— remains substantially stationary until the side of the case —15— having stops —18— thereon comes into contact with the nut thereby interlocking the teeth upon the nut with the stops upon the case. In this condition the nut is prevented from rotation and its movement along the shaft results in positive rotation of the shaft.

40 Upon the reverse movement as under the action of spring —30—, the handle —26— moves the case along the shaft, the nut —14— remaining in stationary condition until cover —19— comes into contact with the nut, the teeth upon the nut being thereby released from engagement with the stops —18—, thereby permitting the nut to freely rotate within the case whereby the return movement of the case and nut along the 45 shaft is effected without rotation of the shaft and without interfering with the continuance of its rotation, due to the free rotation of the nut within the case.

The case —15— is provided with a suitable cover —19— secured thereto in any suitable manner and adapted to inclose the nut —14—. The nut —14— has a central opening —20— of angular form adapted to substantially fit the shaft —11— for trans-

lating movement of the nut longitudinally of the shaft into rotary movement of the shaft, and, as shown in this specific illustration, the opening —20— is substantially square and the inclosing faces —20'— are beveled progressively from one corner at a point adjacent one face to the next succeeding corner and toward the opposite face.

This construction permits the movement of the nut along the shaft to be initiated and continued with a minimum resistance 75 and facilitates the translation of the reciprocal movement of the nut into rotary movement of the shaft, and likewise permits the easy and free return of the nut along the shaft under operating conditions, permitting 80 the rotation of the nut relatively to the case —15—. The faces around and forming the square opening in said nut are, as stated, obliquely disposed and beveled progressively from one corner toward the next 85 succeeding corner and from a point adjacent one face toward the opposite face at the next succeeding corner.

The case —15—, the nut —14— and the cover —19— form a device which is herein-after termed a ratchet clutch, and for the purpose of moving this clutch along the shaft —11— whereby the shaft is rotated by the action of the nut —14—, the case —15— is provided with oppositely disposed pintles 95 —21— and —22— suitably engaged by jaws —23— and —24— formed upon the bifurcated end —25— of an operating lever —26—. The lever —26— is pivoted upon a bolt —27— supported in any suitable manner as by an angle bar —28— operably secured to the casing —6— by screws —29—.

A suitable spring —30— has its central portion tensioned around the bolt —27— and its ends respectively bearing against the 105 casing —6— and the lever —26— on the side of its pivot next the ratchet clutch, so that the spring normally tends to return the lever to starting position after each operation and this return is rapid and easy by 110 reason of the fact that the teeth upon the nut —14— slide over the stops —18— upon this return movement so that the nut itself may rotate, thereby obviating the rotation of the shaft —11— and the vibration of the 115 diaphragm as hereinafter described.

A suitable toothed or cam wheel —31— is mounted on the shaft —11— and preferably has its marginal portion disposed in a plane substantially midway of the diaphragm —1— and operating through a slot —36— formed in the depressed portion —5— of the case section —3—, and its central portion depressed or offset from the plane of its marginal portion, so that the cam wheel may force the vibration of the diaphragm at substantially the central point thereof, and yet the shaft —11— may have

its spirally arranged portion extend somewhat more than one-half the length of the shaft so that a more extensive rotary movement may be imparted to the cam wheel than would be possible if the wheel were journaled upon the central portion of the shaft —11—.

The diaphragm —1— is provided with a suitable contact member —32— cooperating with the wheel —31— to vibrate the diaphragm and this contact member is preferably externally threaded for coaction with an internally threaded bushing —33— secured to the diaphragm in any suitable manner, as by having one of its ends welded over a washer —34— and the contact member may be adjusted toward and from the toothed wheel —31— by means of this threaded relation, and may be locked in any predetermined adjusted position by a lock nut —35—.

Although I have shown and described the invention herein as specifically applied to a signal, it should be understood that such showing is merely illustrative of one application of the invention, which broadly relates to a means for translating longitudinal into rotary movement as specifically set forth in the claims hereto appended and without regard to the specific type of apparatus in connection with which the invention may be used.

Copies of this patent may be obtained for five cents each, by addressing the "Commissioner of Patents, Washington, D. C."

What I claim is:

1. In a signal, a spiral shaft of angular cross section, a nut having an angular opening substantially fitting the shaft, the faces around the angular opening being beveled progressively from one corner toward the next succeeding corner. 35

2. In a signal, a spiral shaft of angular cross section, a nut having an angular opening substantially fitting the shaft, the faces around the angular opening being beveled progressively from one corner and at a point adjacent one face to the next succeeding corner and toward the opposite face. 45

3. In a mechanical movement device, a square shaft having a portion twisted to form spiral pathways, a nut having a square opening adapted to substantially fit the shaft and mounted on the shaft and movable longitudinally of the same, the faces around the square opening in said nut being beveled progressively from one corner and at a point adjacent one face to the next succeeding corner and toward the opposite face. 55

In witness whereof I have hereunto set my hand this second day of June, 1914.

WILLIAM SPARKS.
